[57] **CLAIM**

The ornamental design of a crib endboard frame, as shown and described.

DESCRIPTION

FIG. 1 is a top perspective view showing a crib endboard frame according to our new design;

FIG. 2 is a top plan view thereof;

FIG. 3 is a front elevation view thereof;

FIG. 4 is a side elevation view thereof, the opposite side being a mirror image thereof; and,

FIG. 5 is a rear elevation view thereof.

The portions shown in dotted lines form no part of the claim design. The bottom view also forms no part of the claimed design.
